ATTORNEY.

UNITED STATES PATENT OFFICE.

LEANDRO MAZZOCO, OF LYNN, MASSACHUSETTS.

MEANS FOR SECURING THE STRINGS OF MUSICAL INSTRUMENTS.

1,416,568.

Specification of Letters Patent. Patented May 16, 1922.

Application filed August 24, 1920. Serial No. 405,777.

To all whom it may concern:

Be it known that I, LEANDRO MAZZOCO, a subject of the King of Italy, residing at Lynn, in the county of Essex and State of 5 Massachusetts, have invented certain new and useful Improvements in a Means for Securing the Strings of Musical Instruments; and I do hereby declare the following to be a full, clear, and exact description of the invention, such as will enable others skilled in 10 the art to which it appertains to make and use the same.

This invention relates to means for securing the strings of musical instruments, and the 15 object is to provide means especially adapted for retaining the strings of a violin under proper tension, after the tuning operation has been completed, so that assuming that the pegs do not slip, any change in the length of 20 the strings, due to the weather, or other causes, will be automatically compensated for, thereby maintaining the pitch or tone for a long period.

A further object is to provide increased 25 flexibility, permitting of greater facility in fingering the strings, and providing greater freedom of vibration.

A further object is to provide means for 30 securing the strings resiliently by providing springs of different tension for the several strings, with a view to prolonging the life of the strings and increasing the volume, purity, and carrying power of the notes.

A still further object is to provide a tail- 35 piece, which may be of any suitable design, so far as general construction is concerned, but which is provided with means whereby the strings are readily connected therewith, and with the resilient devices.

40 A still further object is to provide a tail-piece having a recessed portion within which the strings are mounted, or across which they are stretched, particular means being provided for retaining one end of each spring, 45 and for guiding that end of the spring to which the string is attached.

With the foregoing and other objects in view, the invention consists in the novel construction, combination, and arrangement of 50 elements hereinafter described and claimed.

In the accompanying drawing:

Figure 1 is a view of a tail-piece in bottom plan, with the springs in operative position.

Figure 2 is a view in longitudinal section. 55

Figure 3 is a view of one of the springs, detached.

Figure 4 is a view of one end of the tail-piece showing the slotted portion through which the loop members formed on the 60 spring are passed in assembling the device.

In carrying out my invention I employ a tail-piece 10 of any suitable construction, but provided with a recess 12 opening toward the lower side of the tail piece, the end wall 14 of the tail piece remaining intact but being provided with slots 15, for the purpose indicated below.

The springs 16, 17, 18 and 19 vary in size 70 according to the tension required, and each includes a loop portion 20 adapted for engagement by a transverse pin or rod 21 which passes through an aperture 22 extending transversely of the tail-piece.

Formed on the opposite end of each spring 75 and preferably of the same piece of wire, suitably flattened out, is a loop 23, of the form shown. Loop portions are passed through the slots 15 before mentioned, in assembling the device. The object in making 80 the loop to which the string is attached, of one piece with spring per se, is to avoid false vibration. This loop will be covered with a coating of rubber designated 24, the spring being of steel. 85

The tail piece may be made of metal, wood, such as ebony, or of composition, and it is obvious that details of construction may be varied within the scope of the appended claims. 90

It should be added that when the string is under tension, the shank portion of the spring does not touch the edges of the slot in the end of the tail piece, but is absolutely free to vibrate. 95

Having thus described the invention, what I claim is:—

1. In combination with a tail piece of a musical instrument, a plurality of coil springs each having an eyelet, a securing pin 100 common to said eyelets to connect the springs to the tail piece, and strings to which said

springs are secured to function during action and when at rest.

2. In combination with a musical string, a spring to mount the same, and a sound insulating medium engaged by the string and disposed intermediate the string and spring.

3. In combination with a musical string, a spring having an eyelet to which the string

is connected, and a sound insulating medium on the eyelet directly engaged by the string. 10

In testimony whereof I affix my signature in presence of two witnesses.

LEANDRO MAZZOCO.
